FIG. 1

FIG. 2

FIG. 3

FIGURE 1 is a perspective view taken from the front end and the left side of a combination gasoline pump dispenser and product storage unit showing my new design, the right side being a mirror image of the left side.

FIGURE 2 is a perspective view taken from the back end and left side thereof.

FIGURE 3 is a front perspective view, the cover being in a partially open position and the lower portion being omitted for convenience of illustration.

The essential features of the design reside in the solid line portions thereof.

I claim:

The ornamental design for a combination gasoline pump dispenser and product storage unit, substantially as shown and described.
